UNITED STATES PATENT OFFICE.

FREDERICK SCHWANHAUSSER, OF JERSEY CITY, NEW JERSEY.

FRAME FOR MAKING SHADE-CLOTH.

SPECIFICATION forming part of Letters Patent No. 351,206, dated October 19, 1886.

Application filed June 19, 1885. Serial No. 169,165. (No model.)

To all whom it may concern:

Be it known that I, FREDERICK SCHWANHAUSSER, of Jersey City, county of Hudson, and State of New Jersey, have invented certain new and useful Improvements in Frames for Making Shade-Cloth, of which the following is a specification.

This invention has reference to an improved frame to be used in the manufacture of shade-cloths of considerable length; and the invention consists of a cloth-stretching frame that is suspended from hangers pivoted to the beams of the building, said hangers being raised by cords and pulleys, and supported in raised position by pivoted and spring-actuated hooks applied to the beams. The lower end of the cloth-frame is provided with a suitable tackle for stretching the frame after the cloth has been sized and placed into raised position, so that the frame is out of the way of the next adjoining frame back of the same.

In the accompanying drawings, Figure 1 represents a plan of a factory arranged with my improved frames for making shade-cloth. Fig. 2 is a side elevation of one of the beams, showing a cloth-frame in section and the means for suspending the same. Fig. 3 is a detail vertical transverse section through the beam on line *x x*, Fig. 1, showing the supporting-hook for the hanger of the cloth-frame, and Fig. 4 is a detail side view of the hooked rod for transferring the lifting-cords from the front to the rear pulleys of the beams.

Similar letters of reference indicate corresponding parts.

In the drawings, A represents the supporting-beams of a factory for making shade-cloth. To the beams A are pivoted a number of hangers, B, from which are suspended by pivot-rods B' the cloth-frames C, which are stretched by suitable tackle, b b', connecting the lower end of the frames with eyes b² on the floor. In front of each hanger B is pivoted to the beams a spring-actuated hook, D, that oscillates at right angles to the beam. A cord, E, is attached to the lower part of the hanger, and passed either over a pulley, d, in front of the hanger or over a pulley, d', back of the same, as the case may be, according to the progress of the work. By pulling the cord E the hanger B and the cloth-frame C are raised in the position shown in dotted lines in Fig. 2 until the

hanger passes sidewise of the pivot-hook D, so as to press it back until the spring D' of the same throws it below the hanger B, and supports 55 the latter in inclined position. The cloth-frame is thereby raised above the ground, and is then in a position to be stretched by the stretching-tackle.

The cloth-frames are preferably made about 60 sixty feet in length, and are supported on six hangers applied to every fourth beam of the building. About six inches back of the first row of hangers B is pivoted at the other side of the beams a second set of hangers, to which 65 is hung a second cloth-frame, while a third cloth-frame is suspended from a third set of hangers, pivoted about six inches back of the second hanger to the second, sixth, tenth, &c., beam, while the fourth hanger is suspended 70 from a fourth set of hangers applied to the other side of said beams. The fifth and sixth cloth-frame are pivoted in the same manner to hangers of the third, seventh, eleventh, &c., beam, the seventh and eighth cloth-frames to 75 the fourth, eighth, twelfth, &c., beam, and so on, so that a large number of cloth-frames is hung at intervals of six inches from hangers of the beams.

The cloth is applied to the cloth-frames when 80 they are in the position shown in full lines in Fig. 2. When the cloth has been applied to the cloth-frame, it is sized, after which the cloth-frame is raised, so that the hangers B are supported on the hooks D, as shown in dotted 85 lines at the right-hand side of Fig. 2. In this position the cloth is stretched, by pulling the tackle, and allowed to dry. A cloth is then applied to the next following frame C, sized in the same way and raised in the same manner 90 as the first cloth and stretched. After the cloth on every frame has thus been sized, placed into raised position, and stretched, they are allowed to remain in this position until the shade-cloths are perfectly dry. The last cloth-frame is then 95 lowered first by releasing the hooks D by means of the cords D', Fig. 3, and painted in oil at both sides, when oil shade-cloths have to be made, and then raised into the position shown in dotted lines at the left-hand side of Fig. 2 100 by transferring the cords E to the rear pulleys, d', by means of the hooked rod F, (shown in Fig. 4,) and attaching them to the floor. In this position the cloth-frames do not require

stretching, but simply drying of the coat of oil-paint. The second cloth-frame is then lowered, painted, and raised again into the position shown in dotted lines in Fig. 2, and so on 5 all through.

By this method of suspending the cloth-frames sufficient space is provided between the cloth-frames for working on the shade-cloths, so as to conveniently accomplish the different 10 manipulations required in sizing and painting the cloths. A large number of cloth-frames can thus be suspended close together in a factory without waste of room, whereby the manufacture of long shade-cloth is facilitated and 15 expedited.

Having thus described my invention, I claim as new and desire to secure by Letters Patent—

1. The combination of the supporting-beams, 20 hangers pivoted to the beams, intermediate

pivot-rods, a cloth-frame, spring-pressed hooks pivoted to the beams, and stretching-tackle connecting the lower part of the cloth-frame with the floor, substantially as set forth.

2. The combination of the supporting-beams, 25 pivoted hangers, intermediate rods, a cloth-frame, pivoted and spring-pressed hooks, stretching-tackle connecting the floor with the lower part of the cloth-frame, cords attached to the hangers, and pulleys applied to the beams 30 in front of and back of the hangers, substantially as set forth.

In testimony that I claim the foregoing as my invention I have signed my name in presence of two subscribing witnesses.

FREDERICK SCHWANHAUSSER.
